Patented Aug. 22, 1967

208,367

LIGHT-RAY BAFFLE

Jacob H. Blitzer, Jr., Los Angeles, Calif., assignor to
Integrated Ceilings, Inc., Los Angeles, Calif., a corpo-
ration of California

Filed May 9, 1966, Ser. No. 2,222

Term of patent 14 years

(Cl. D48—16)

FIG. 2.

FIG. 3.

FIG. 4.

FIG. 5.

FIGURE 1 is perspective view of a light-ray baffle showing my new design;

FIG. 2 is a bottom plan view thereof;

FIG. 3 is a side elevational view thereof;

FIG. 4 is a sectional view thereof, on an enlarged scale, taken along the line 4-4 on FIG. 2;

FIG. 5 is a sectional view thereof, on an enlarged scale, taken along the line 5-5 on FIG. 2.

I claim:

The ornamental design for a light-ray baffle, substantially as shown.
